UNITED STATES PATENT OFFICE.

EDWARD G. SYLVESTER, OF HONOLULU, TERRITORY OF HAWAII.

HAIRPIN.

Application filed May 7, 1925. Serial No. 28,707.

This invention relates to an improvement in hair pins especially adapted for use with bobbed hair, and has for its object the provision of an improved hair pin which is well 5 adapted to engage with the hair in the ordinary manner to hold the same as fixed without danger of the pin slipping from its place, the pin being self-locking when engaged with the hair.

10 A further object is the provision of a hair pin having the advantages and capacities mentioned and which has all the advantages of the ordinary hair pin in addition to being self-locking, and which is of simple and 15 durable construction, reliable and effective in operation and easy and comparatively inexpensive to manufacture.

Other objects and advantages reside in certain novel features of the construction, 20 arrangement and combination of parts which will be more fully described and particularly pointed out in the appended claim, reference being had to the accompanying drawings forming a part of this specification, and in which:

25 Figure 1 is a view in elevation showing a hair pin constructed in accordance with the present invention, the arms of the hair pin being shown spread, and

30 Figure 2 is a view similar to Fig. 1 but showing the arms of the hair pin interlocked.

Referring to the drawings, the numeral 1 designates the head or body portion of the 35 hair pin which takes the form of a bight or bend from which the arms or prongs 2 and 3 project. The general form of the hair pin is the same as that of the conventional pin. Midway between their ends the arms 40 2 and 3 are formed with crimps 4 and 5 to better adapt the pin to engage and hold the hair. The arm 3 is longer than arm 2 and is substantially straight from the point at which it joins the body portion to its extreme 45 outer end except for the crimp 5 therein. The arm 2 is likewise substantially straight

from the point at which it joins the body portion 1 to a point adjacent its outer end except for the crimp 4. However, the extremity of the arm 2 is formed with a hook 50 6 designed to interlock with the outer end of the arm 3, as shown in Figure 2. The hook 6 opens outwardly with respect to the arm 2 and is gradually curved to render it easily engageable with and disengageable 55 from the arm 3.

With this arrangement the arms of the hair pin present continuous hair-engaging surfaces for practically their entire length so that all of the advantages of the ordinary 60 hair pin is had. Along with these advantages is the additional advantage obtained by virtue of the interlocking of the extreme outer ends of the hair pin, whereby the hair pin is held in position and the hair better 65 confined on and between the hair-engaging surfaces presented by the arms of the pin for practically the entire length of the arms.

I claim:

A hair pin having a body portion and a 70 pair of arms of uniform cross section throughout their extent, one of said arms being substantially straight from the body portion to its free end, the other arm being formed with a gradually curved outwardly 75 opening hook at its outer extremity engageable and extendable around the outer end of the straight arm in substantially encircling engagement to interlock the arms, the arm with the hook being substantially 80 straight for practically its entire length, that is, from its head to its hook, whereby the arms of the hair pin present continuous hair-engaging surfaces for practically their entire length between which the hair is confined when the arms are interlocked, the terminal of said hook extending substantially 85 longitudinally of the pin to facilitate its insertion in and removal from the hair without entanglement.

EDWARD G. SYLVESTER.
